ROTATING GAME POINTER

Charles Benker, North Attleboro, Mass.

Application February 26, 1946, Serial No. 650,239

12 Claims. (Cl. 273—141)

1

This invention relates to a game apparatus of a type which may be utilized for the playing of the game "Bingo," which may provide amusement for a large number of people.

In the operation of certain amusement devices, some means is provided by which a player indicates whether or not a certain number appears in the game. There is some possibility of a person's missing hearing the number or misunderstanding the number, or otherwise being at fault in taking some action such as covering the number which appears, which human errors may disturb the game which is being played.

One of the objects of this invention is to provide an apparatus which will positively indicate a number which has been chosen in the playing of the game, thus removing the chance of human fault, which may cause an error in the playing of the game.

Another object of this invention is to provide means by which the playing of the game may be made automatic with little chance of error.

Another object of this invention is to provide an apparatus wherein if a number has once appeared in the game, it cannot again appear until the game apparatus has been reset.

Another object of this invention is to provide a game which may be played more quickly by reason of the instantaneous indication to each player of the number which has been chosen.

Another object of this invention is to provide an arrangement whereby all of the playing boards which are used in the game will operate simultaneously as to any number should the number which is chosen appear on that board.

Another object of this invention is to provide an arrangement so that all of the boards may be reset to starting position once the game is completed.

A more specific object of the invention is the provision of an apparatus of this character which can be manufactured at a comparatively low cost of production and which will be satisfactory in use.

With these and other objects in view, the invention consists of certain novel features of construction, as will be more fully described and particularly pointed out in the appended claims.

In the accompanying drawings:

Fig. 1 is a central sectional view of a fragmental portion of game apparatus embodying my invention;

Fig. 2 is a view of a portion of the apparatus shown in Fig. 1 showing the selector arm in a different position;

2

Fig. 3 is a plan of a fragmental portion of the apparatus shown in Fig. 1;

Fig. 4 is a sectional view of a bank of interceptors;

5 Fig. 5 is a sectional view of the switch employed in this apparatus;

Fig. 6 is a plan view of one of the individual boards or devices forming part of this invention;

10 Fig. 7 is a diagrammatic view illustrating the electric circuit between the selector mechanism and the individual boards.

In carrying out the invention as applied to the game of "Bingo," I provided a plurality of play cards or boards and these are divided in a manner 15 so as to provide five vertical and five horizontal rows of numbered squares. The numbers which are selected for each of the squares will be so selected that each game board will be different. In each square a lamp will be mounted and all 20 lamps from like numbered squares from all of the play boards will be electrically connected to be lighted as a group. A switch is provided for controlling all of the lamps in like numbered squares in all of the boards. Each switch is controlled by an interceptor which is movable by means of a selector element.

With reference to the drawings for a more detailed description of the invention, 10 designates generally a fragmentary portion of the 30 selector part of my invention. The selector may consist of a frame work 11 supporting an upper deck 12, a lower deck 13, and an intermediate deck 14. The upper deck 12 is provided with a plurality of openings 15. These openings are equally 35 spaced from each other and may be positioned on a circle described from the center of the deck. The intermediate deck 14 is also provided with a plurality of openings 16 similarly spaced and in line with the openings 15. Through these openings 40 are slidably mounted interceptors 17.

There are a plurality of these interceptors, there being one for each group of lamps. Each interceptor is identical in construction and comprises a body portion 18 having a slot 19 extending laterally therein and a reduced portion providing a shank 20 which terminates in an enlarged head 21. The body 18 is slidably mounted in one of the openings 15 and extends above and below the deck 12 with the slot 19 at a location below the deck 12. The shank 20 depends from the body and extends through an aligned opening 16 in the deck 14 with the head 21 at a location below the deck. Between each interceptor on the upper surface of the deck are positioned guides 22. 45 These guides may comprise a single annulus 22'

provided with openings corresponding in number to the openings 15 and spaced to be in alignment with the openings 15. The material between the opening will be provided in a V formation with the apex thereof of a height to extend a distance above the interceptors (see Fig. 4).

On the intermediate deck 14 and adjacent to each interceptor is positioned an electrical switch 23. This switch better shown in section in Fig. 5 is of a toggle type and has a pivoted arm 24 extending outwardly of the body of the switch. The outer free end of the arm is received in the slot 19 of the interceptor. A pull spring 25 has one end thereof anchored to the wall 26 of the switch at a point thereon midway between the throw of the arm 24. The other end of the spring is anchored to the arm 24 at a location thereon on the longitudinal axis thereof and on the side of the pivot distal from the wall 26. The spring is of sufficient strength so as to retain the interceptors in the upper position shown in Fig. 1 when the switch is in the open position. When the interceptor is moved downwardly with sufficient force so as to overcome the pull of the spring 25, the same will move the arm 24 to close the switch. The contact C is insulated from the body of the switch and a conductor W extends from the contact and forms part of the wiring circuit as will be hereinafter described. The inner end of the arm 24 forms the other contact of the switch and with the body of the switch is placed in the ground of the circuit which may include the deck 14.

In order to select and move an interceptor to actuate a switch a selector element is provided. The selector element is herein shown in the form of an arm 27 which is mounted on a vertically disposed shaft 28. This shaft is slidably mounted in the deck 12, extends centrally through the decks 13, 14, and finds bearing at its lower end in a support 29. Secured to this shaft at the lower portion thereof is a friction wheel 30, by means of which the shaft is rotated to swing the arm 27 over the interceptors 17. The means for actuating this shaft herein shown consists of an electrically operated reversible motor 31 having secured to the shaft thereof, a friction wheel 32 which engages with the wheel 30.

In order to provide that the selector chosen shall be more or less according to chance, I provide for the free rotation of the arm 27 and also for a gravitational movement of the arm toward the interceptor so that this arm upon coming to rest will engage an interceptor and by the weight of its associated elements will move this interceptor and the arm 24 of the switch connected thereto so as to close the switch associated with the chosen interceptor. Accordingly, I mount on the shaft 28 an anti-friction device 33 comprising discs 33', 33'', between which are positioned ball bearings. The disc 33' is secured to the shaft 28 while the disc 33'' is rotatable relative to the shaft 28 and disc 33'.

On the shaft of the motor 31 is mounted a cam wheel 34, the peripheral cam surface of which engages the disc 33'' and provides for vertical reciprocation of the shaft 28. The cam surface is such as to permit a period of engagement of friction wheels 30, 32 to establish sufficient velocity in the rotation of the arm to provide a momentum force of a degree as not to be suddenly arrested by its engagement with the guides in its movement over the interceptors, that the arm may jump from between one interceptor to

another before finally coming to rest. It will be apparent that as the arm is permitted to lower the friction wheels 30 and 32 will become disengaged and free rotation of the shaft 28 and arm 24 carried thereby will be had. In order to block the arm 27 from engagement with an interceptor once having been moved, I provide a blocking member 35 for each interceptor. Each member 35 is pivotally mounted in a support 36 by means of a pivot pin 37. Each blocking member 35 has an arm 38 extending from one side of the pivot and is initially positioned to extend horizontally and radially in line with the center of an adjacent interceptor and beneath the initial path of travel of the selector 27. The blocking member 35 is also provided with an arm 39 extending from the opposite side of the pivot 37 and at right angles to the arm 38. This arm 39 is weighted so as to overbalance the arm 38 and a stop 40 in the form of an annulus is positioned to engage the arm 39 so as to prevent movement of member 35 in a counter-clockwise direction.

The arm 27 is constructed in two sections. The inner section has its end bifurcated as best shown in Fig. 3 providing a slot 41 in which is received the outer section 42 of the arm. The section 42 is pivoted to the inner section as at 43. A stop 44 is provided on the inner section of the arm on one side of the pivot to be engaged by and arrest any individual movement of section 42 in a clockwise direction. The section 42 is pivoted at a location thereon so as to be overbalanced and be normally biased against stop 44. As the shaft 28 and arm 27 are permitted to move vertically downwardly by action of the cam 33, the end extremity 46 of the outer section will engage the arm 38 and move the same about the pivot 37 in a clockwise direction sufficiently so as to be overbalanced by the weighted arm 39. The end extremity of the arm 38 will engage against the base of the support 36 as seen in Fig. 2 and arrest movement of member 35 and position the arm 39 to extend horizontally in the path of the downward movement of the arm 27. The arm 39 will remain in this position until reset and will block the engagement of the arm 27 with the interceptor associated with the particular blocking member associated therewith upon subsequent rotation of selector 27. When the selector is moved upwardly out of engagement with the chosen interceptor, the end portion 46 of the selector will engage the arm 35 and be moved thereby about the pivot 43 in a counterclockwise direction until sufficient movement has occurred therein for the same to escape, from beneath arm 39.

After a sufficient number of the interceptors have been moved to close the switches associated therewith, the interceptors may be moved to initial position by means of a plate 47 which is slidably mounted for vertical movement on a bearing support 48 depending from the intermediate deck 14. This plate 47 is of a diameter to extend beneath heads 21 of the interceptors and is provided with a depending hub 49 having an annular groove 50 provided therein. A collar 51 secured to the bearing support 48 provides an abutment against which the plate 47 rests. A lever 52 is pivoted as at 53 to a depending bracket 54 and is provided with spaced ears 55. From these ears there extend pins or trunnions 56 which engage in the slot 50. To reposition the interceptors to initial position, the lever 52 is manually raised and through the pin connection 56 will move the plate 47 vertically to engage the

heads 21 of the interceptors and raise the same to initial position.

Each blocking member 35 has a pin 57 extending therefrom and provided with an eye in which is secured an end of a cord 58. The cord passes through aligned openings 59, 60, in the decks 12 and 14. The lower end of the cord is knotted as at 61 and supports a washer 62. An annular plate 63 is slidably mounted on the bearing support 48 and has a boss 64 depending therefrom, the lower end of which is provided with an annular groove 65. This annular groove is engaged by trunnions 66 extending from a hand operating lever 67 which is pivoted as at 68 from a support 69 depending from the lower deck 13. This plate 63 is provided with opening 70 which aligns with the openings 59, 60 and through which the cord 58 passes. Moving the lever 67 in a downward direction will move the disc 63 downwardly to engage the washers 62 and exert a pull on the cords 58 to swing the blocking members 35 to initial position. The disc 63 is returned and retained in its normal position by means of a compression spring 71 surrounding the boss 64 and acting between the lower deck 13 and the plate 63.

In Fig. 6 I have shown an individual board which is to be placed before a player. There will be a plurality of such boards one for each player. Each board is divided so as to provide five vertical and five horizontal rows of squares.

The square will be numbered with a numeral chosen within a particular range of numerals, for example, from 1 to 75. The numbers which are selected for each of the squares will be so selected that each game board will be different. In each square a lamp 72 will be mounted and all of the lamps from the numbered squares from all of the play boards will be electrically connected to be controlled by one of the switches 23 so as to be lighted as a group when the particular switch 23 is actuated by the movement of the interceptor associated therewith. For instance, if the interceptor selected were that operating the switch 23 controlling the lamps on squares Number 1, all lamps for Number 1 squares would be lighted, such for instance as the lamp designated 73, 73' and 73'' in Fig. 7. Were another interceptor selected, a similar switch 23' would be closed and in this instance the lead W' would cause all lamps 74 to be lighted. Similarly other lamps 75 will be connected to switch 23'' through lead W''. The electric circuit includes energizing means 76 ground as at 77 and has a common lead 78 to all of the ground portion of the switches. It will be understood that there will be as many interceptors and switches as numerals in the particular range of numerals chosen.

In playing the game of "Bingo" or similar games with the apparatus herein described, the player chooses a play board or boards which have been previously arranged in proper supports, such as a table and the like. The motor is set in action and through the cam action the selector arm 27 is actuated to move to select an interceptor and move the same to close the switch associated therewith as previously described. The dwells on the cam are chosen to permit ample time for the arm 27 to come to rest after free rotation prior to being raised out of contact with the interceptor so as to move an interceptor a sufficient distance to permit the spring 25 of the toggle switch to be positioned to finish the movement of the switch arm 24 to close the circuit 75

as is common in toggle type switches. This action will continue until all the lamps of a play board have been lighted in a previously defined order. The first board so lighted of course wins the game. The interceptors and switches are returned to initial position in the manner previously described for the start of each new game.

During the play of the game the operator may at will reverse the direction of rotation of the motor 31 by manipulation of switch 31a in the motor circuit so that chance selection of an interceptor may be increased.

I claim:

15. A game comprising a bank of movably mounted interceptors for a movable element mounted for positive and free rotational and gravitational movement, driving means engageable with said movable element for rotating said element over said interceptors, and means operable for disengagement of the driving means from said movable element to permit free movement thereof over said interceptors and gravitational movement of said element toward said interceptors to contact and move one thereof upon said element coming to rest.
20. A game comprising a bank of movably mounted interceptors for a movable element, mounted for positive and free rotational and gravitational movement, driving means engageable with said movable element for rotating said element over said interceptors, means operable for disengaging the driving means from said movable element to permit free movement thereof over said interceptors and gravitational movement of said element toward said interceptors to contact and move one thereof upon said element coming to rest and means responsive to the movement of said interceptors to actuate an electric circuit, including a plurality of lamps.
25. A game comprising a bank of movably mounted interceptors for a movable element mounted for positive and free rotational and gravitational movement, driving means engageable with said movable element for rotating said element over said interceptors, means operable for disengagement of the driving means from said movable element to permit free movement of said element and gravitational movement of said element toward said interceptors to contact and move one thereof upon said element coming to rest, means responsive to the movement of said interceptors to actuate an electric circuit including a plurality of lamps, and blocking means movably mounted and positioned in the path of movement of said element to be engaged thereby and moved in position to block engagement of said element with a once moved interceptor.
30. A game comprising a bank of movably mounted interceptors for a movable element mounted for positive and free rotational and gravitational movement, driving means engageable with said movable element for rotating said element over said interceptors, means operable for disengaging the driving means from said movable element to permit free movement of said element over said interceptors and gravitational movement of said element toward said interceptors to engage therewith and move one thereof upon said element coming to rest.
35. A game comprising a bank of movably mounted interceptors for a movable element mounted for positive and free rotational and gravitational movement, driving means engageable with said movable element for rotating said element over said interceptors, and cam means for disengaging said driving means to permit free movement of said element over said interceptors and gravitational movement of said element towards said interceptors to engage therewith and move one thereof upon said element coming to rest.
40. A game comprising a bank of movably mounted interceptors for a movable element mounted for positive and free rotational and gravitational movement, driving means engageable with said movable element for rotating said element over said interceptors, means operable for disengagement of the driving means from said movable element to permit free movement of said element over said interceptors and gravitational movement of said element toward said interceptors to contact and move one thereof upon said element coming to rest, means responsive to the movement of said interceptors to actuate an electric circuit including a plurality of lamps, and blocking means movably mounted and positioned in the path of movement of said element to be engaged thereby and moved in position to block engagement of said element with a once moved interceptor.
45. A game comprising a bank of movably mounted interceptors for a movable element mounted for positive and free rotational and gravitational movement, driving means engageable with said movable element for rotating said element over said interceptors, means operable for disengaging the driving means from said movable element to permit free movement of said element over said interceptors and gravitational movement of said element toward said interceptors to engage therewith and move one thereof upon said element coming to rest.
50. A game comprising a bank of movably mounted interceptors for a movable element mounted for positive and free rotational and gravitational movement, driving means engageable with said movable element for rotating said element over said interceptors, means operable for disengaging the driving means from said movable element to permit free movement of said element over said interceptors and gravitational movement of said element toward said interceptors to contact and move one thereof upon said element coming to rest, means responsive to the movement of said interceptors to actuate an electric circuit including a plurality of lamps, and blocking means movably mounted and positioned in the path of movement of said element to be engaged thereby and moved in position to block engagement of said element with a once moved interceptor.
55. A game comprising a bank of movably mounted interceptors for a movable element mounted for positive and free rotational and gravitational movement, driving means engageable with said movable element for rotating said element over said interceptors, and cam means for disengaging said driving means to permit free movement of said element over said interceptors and gravitational movement of said element towards said interceptors to engage therewith and move one thereof upon said element coming to rest.
60. A game comprising a bank of movably mounted interceptors for a movable element mounted for positive and free rotational and gravitational movement, driving means engageable with said movable element for rotating said element over said interceptors, and cam means for disengaging said driving means to permit free movement of said element over said interceptors and gravitational movement of said element towards said interceptors to engage therewith and move one thereof upon said element coming to rest.
65. A game comprising a bank of movably mounted interceptors for a movable element mounted for positive and free rotational and gravitational movement, driving means engageable with said movable element for rotating said element over said interceptors, and cam means for disengaging said driving means to permit free movement of said element over said interceptors and gravitational movement of said element towards said interceptors to engage therewith and move one thereof upon said element coming to rest.
70. A game comprising a bank of movably mounted interceptors for a movable element mounted for positive and free rotational and gravitational movement, driving means en-

gageable with said movable element for rotating said element over said interceptors, cam means operable for the disengagement of said driving means to permit free movement of said element over said interceptors and gravitational movement of said element towards said interceptors to engage therewith and move one thereof upon said element coming to rest and blocking means movably mounted and operable by said element to be moved into position to block engagement of said element with a once moved interceptor.

6. A game comprising a bank of movable interceptors for a movable element mounted for positive and free rotational and gravitational movement, frictional operated means engageable with said movable element for rotating the same over said interceptors, means operable for disengagement of said frictional means to permit free rotation and gravitational movement of said element toward said interceptors to contact and move one thereof upon said element coming to rest.

7. A game comprising a bank of movably mounted interceptors, an arm mounted for positive and free rotational movement over said interceptors, driving means, means connecting said arm to said drive means for rotating said arm over and out of contact with said interceptors, means for disengaging the first said means with said driving means to permit free rotation and gravitational movement of said arm towards said interceptors to contact and move one thereof upon said arm coming to rest, and means responsive to the movement of said interceptors to actuate an electric circuit, including a plurality of lamps.

8. A game comprising a bank of movably mounted interceptors, an arm mounted for positive and free rotational movement over said interceptors, driving means, frictional operated

means engageable with said driving means for rotating said arm over said interceptors, cam operated means for disengaging the frictional operated means from said driving means to permit free rotation and gravitational movement of said arm toward and into engagement with said interceptors and move one thereof upon said arm coming to rest.

9. A game as set forth in claim 1 wherein said interceptors comprise rods vertically disposed.

10. A game as set forth in claim 1 wherein guides are positioned between interceptors.

11. A game as set forth in claim 10 wherein the said guides are V-shaped.

12. A game comprising an electric circuit including a plurality of lamps and switches, a contact for each of said switches, an element mounted for rotational movement over said contacts and for gravitational movement towards said contacts, driving means, means for connecting said driving means to said element for the positive rotation of said element and means for disengaging said driving means from said element to permit free rotation and gravitational movement of said element toward and into engagement with said contacts to move one thereof to actuate the switch controlled thereby upon said element coming to rest.

30 CHARLES BENKER.
